UNITED STATES PATENT OFFICE

HENRY L. SCHROEDER, OF CHICAGO, ILLINOIS

DESIGN FOR A SCORE BOARD OR SIMILAR ARTICLE

Application filed February 21, 1930. Serial No. 34,602. Term of patent 3½ years.

To all whom it may concern:

Be it known that I, HENRY L. SCHROEDER, a citizen of the United States, residing at Chicago, in the county of Cook and State of Illinois, have invented a new, original, and ornamental Design for Score Board or Similar Article, of which the following is a specification, reference being had to the accompanying drawing, forming a part thereof.

In the drawing,

The figure is a plan view of a score board or similar article, showing my new design.

I claim:

The ornamental design for a score board or similar article, substantially as shown.

HENRY L. SCHROEDER.
